UNITED STATES PATENT OFFICE

JOSEPH O. POLLACK, OF CHICAGO, ILLINOIS, ASSIGNOR TO J. O. POLLACK & COMPANY,
OF CHICAGO, ILLINOIS, A CORPORATION OF ILLINOIS

DESIGN FOR A NURSE'S BADGE

Application filed July 31, 1931. Serial No. 40,740. Term of patent 7 years.

To all whom it may concern:

Be it known that I, JOSEPH O. POLLACK, a citizen of the United States, residing at Chicago, in the county of Cook and State of Illinois, have invented a new, original, and ornamental Design for a Nurse's Badge, of which the following is a specification, reference being had to the accompanying drawings, forming a part thereof.

Fig. 1 is a front elevational view of a nurse's badge showing my new design; and Fig. 2 is a side elevational view of the badge.

I claim:

The ornamental design for a nurse's badge, as shown.

JOSEPH O. POLLACK.
